United States Patent Office

Des. 229,045
Patented Nov. 6, 1973

229,045

STEP FOR A MOTOR VEHICLE

Carl Woodall, Downey, Calif., assignor to James Carl
Woodall, Los Angeles, Calif.

Filed Aug. 16, 1971, Ser. No. 172,379

Term of patent 14 years

Int. Cl. D12—16

U.S. Cl. D14—13

FIG. 5.

FIG. 1 is a perspective view of a step for a motor vehicle showing my new design;

FIG. 2 is a rear elevational view;

FIG. 3 is a left side elevational view;

FIG. 4 is a top plan view; and

FIG. 5 is a bottom plan view.

I claim:

The ornamental design for a step for a motor vehicle, as shown.
